UNITED STATES PATENT OFFICE.

GEORGE O. LEOPOLD, OF PHILADELPHIA, PENNSYLVANIA, ASSIGNOR TO NORTH BRO'S M'F'G CO., OF PHILADELPHIA, PENNSYLVANIA, A CORPORATION OF PENNSYLVANIA.

DRILL.

1,103,783.

Specification of Letters Patent. Patented July 14, 1914.

Application filed September 11, 1913. Serial No. 789,313.

To all whom it may concern:

Be it known that I, GEORGE O. LEOPOLD, a citizen of the United States, residing in Philadelphia, Pennsylvania, have invented 5 certain Improvements in Drills, of which the following is a specification.

The object of my invention is to provide a drill with automatic means for stopping longitudinal movement of the drill spindle 10 when it reaches the extreme upper or lower position, and this is accomplished without interfering with the free rotation of the spindle.

In the accompanying drawings:—Figure 15 1, is a side view of the head of a bench drill illustrating my invention and showing the shifter in the mid-position; Fig. 2, is a front view with the shifter in the same position as in Fig. 1; Fig. 3, is a plan view; Fig. 4, 20 is a sectional plan view on the line *a—a*; Fig. 1; Fig. 5, is a perspective view of the pawl carrier; Fig. 6, is a perspective view of the pawl; Fig. 7, is a diagrammatic view showing the shifter in the feeding position 25 and descending; Fig. 8, is a view showing the pawl being shifted by coming in contact with the abutment in the lower position; and Fig. 9, is a view showing the pawl coming in contact with the abutment when in the 30 upper position.

Referring to the drawings, 1 is the frame of the drill in the present instance, which can be supported in any suitable manner according to the type of drill to which the 35 invention is applied. This frame has a bearing 2 for the shaft 3 which is provided with a handle, although a pulley may be substituted for the handle when the drill is driven by power. Secured to the inner 40 end of the shaft 3 is a bevel gear wheel 4 which meshes with a pinion 5 splined to the spindle 6. The spindle, in the present instance, has a longitudinal groove therein and a key on the pinion enters the groove 45 so that while the spindle can move vertically in the pinion it must turn therewith.

7 is a bearing through which the spindle 6 extends. This bearing rests upon the end of the pinion and has an extension forming 50 an outer bearing for the shaft 3, as clearly shown in Figs. 1 and 2. In this bearing is a spring bolt 8 having a handle 9. When in the position illustrated in Fig. 2, this bolt is withdrawn clear of the groove in the 55 spindle 6, but, when the handle 9 is shifted

at right angles, it drops into a slot and the bolt enters the groove in the spindle and prevents it from turning. The object of this construction is to hold the spindle from turning when it is desired to operate the 60 chuck to secure or remove bits from the drill, obviating the necessity for holding the handle. This construction is fully illustrated and described in the Patent No. 1,073,500, dated Sept. 16, 1913, and as it 65 forms no part of the present invention it need not be described in detail.

Loosely mounted on the spindle 6 is a feed screw 10. The lower end of the feed screw rests upon a bearing 11 secured to 70 the spindle, so that the pressure of the spindle, as the tool enters the work, is taken by this bearing. The upper end of the screw rests against a sliding bearing 12 which is held to the spindle by a screw 13 and washer 75 14. This bearing is adapted to slide on the vertical guide 15 which is mounted on the upper portion of the frame 1 and has a stop 16 to limit the upward movement of the 80 sliding bearing 12.

Secured to the feed screw 10 is a ratchet wheel 17, and mounted between the end of the ratchet wheel and the bearing 12 is a carrier 18 in which is mounted a spring 85 pawl 19. This spring pawl is free to turn in the carrier, as illustrated in Fig. 4, so as to feed either to the right or to the left. In the carrier is a notch 20 to receive the handle 21 of the pawl so as to hold the 90 pawl in either of the two positions in which it is adjusted.

Secured to or forming part of the frame 1 is a shifter 22. In the present instance, this shifter is secured to the frame by a screw 23 and has a lower projection 24 and an upper projection 25. The lower projection is in the path of the handle 21 of the pawl 19 when the pawl is descending, and the projection 25 is in the path of the handle of the pawl when the pawl is ascending. 100

In order to cause the carrier 18 to reciprocate, I form an eccentric hole in the carrier, as illustrated in Fig. 4, and mount a roller 26 in a recess in the spindle 6, which forms 105 a cam so that, as the spindle rotates, the carrier will be reciprocated; the carrier being pivotally mounted on a pin 27 projecting from the bearing 12.

Figs. 7, 8 and 9 are diagrams. In Fig. 7, 110

the handle 21 is in position to cause the feed screw and the spindle to descend and the projection 24 of the shifter 22 is in the path of the handle and, as the feed screw reaches 5 the limit of its lowest movement, the handle comes in contact with the projection 24 and is shifted to the position illustrated in Fig. 8, causing the arm to ride on the upper wall of the notch 20 and withdrawing the pawl 10 from engagement with the ratchet wheel 17, stopping the longitudinal movement of the spindle but not interfering with the rotation thereof. When it is wished to reverse the 15 ratchet movement, the handle 21 is turned to the position illustrated in Fig. 9, so that the upper projection 25 of the shifter 22 will be in the path of the handle 21 and, by reversing the rotation of the driving handle, the movement of the spindle and screw will be 20 reversed and the ratchet feed will take place on the upward movement. When the handle 21 comes in contact with the projection 25, it is caused to rotate on the lower wall of the notch 20 and the pawl 19 will be withdrawn 25 from the ratchet wheel. The spindle can then be rotated without further movement of the feed screw. By this construction vertical movement of the spindle in either direction is limited and there is no liability of the spindle, or the feed screw, 30 passing a given point and jamming in the frame due to neglect of the operator.

I claim:—

1. The combination in a drill, of a frame; 35 a spindle; a feed screw on the spindle; a ratchet wheel on the feed screw; a carrier; a spring pawl on the carrier for operating the ratchet wheel; an arm on the pawl for shifting it so that it will feed either to the

right or to the left; a cam on the spindle for 40 actuating the carrier; a shifter on the frame having upper and lower projections, one at one side and the other on the opposite side of the carrier and in the path of the arm of the pawl, so that, when the feed screw 45 reaches the limit of its downward movement, the pawl will be automatically moved out of engagement with the ratchet wheel and, when the screw reaches the limit of its upward movement, the pawl will be automatically thrown out of engagement with the 50 ratchet wheel.

2. The combination in a drill, of a frame; a spindle; means for turning the spindle; a feed screw on the spindle; a ratchet wheel secured to the feed screw; a carrier; a cam on the spindle for vibrating the carrier; a spring pawl on the carrier for operating the ratchet wheel; an arm on the pawl; said carrier having a notch therein arranged to 55 receive the arm when the pawl is in engagement with the ratchet wheel; and a shifter having an upper and a lower projection, one on one side of the pawl and the other on the opposite side thereof and in the path of the 60 arm when it is in either of its two extreme positions, so that, when the arm comes in contact with one of the projections, the pawl will be thrown out of engagement with the 65 ratchet wheel.

In testimony whereof, I have signed my name to this specification, in the presence of two subscribing witnesses.

GEORGE O. LEOPOLD.
